Primary Examiner—Lucy Lieberman
Attorney, Agent, or Firm—Smith-Hill and Bedell**[57] CLAIM**

The ornamental design for a body for a bottle, as shown and described.

DESCRIPTION

FIG. 1 is a front elevation of a body for a bottle showing my new design;

FIG. 2 is a rear elevation thereof;

FIG. 3 is a top plan view thereof; and,

FIG. 4 is a bottom plan view thereof.

The broken lines showing a bottle neck are for illustrative purposes only and do not form part of the claimed design.
